(57) **CLAIM**

The ornamental design for a can shaped disposal bin for a tabletop, as shown and described.

DESCRIPTION

FIG. 1 is a perspective view of the can shaped disposal bin for a tabletop of the instant invention;

FIG. 2 is a top view thereof;

FIG. 3 is a bottom view thereof;

FIG. 4 is a right side view thereof; and,

FIG. 5 is a left side view thereof.

The portions of the figures illustrated in broken lines illustrate portions of the can shaped disposal bin for a tabletop which form no part of the claimed subject matter.
